SEAM FOR WOVEN WIRE FABRIC AND
METHOD OF MAKING THE SAME

Fred Crossman, Shaker Heights, and Earl A. Southam, Cleveland, Ohio, assignors to The Lindsay Wire Weaving Company, Cleveland, Ohio, a corporation of Ohio

Application December 9, 1939, Serial No. 308,452

9 Claims. (Cl. 245—10)

The present invention relates to woven wire belts, particularly for paper making machines of the Fourdrinier type, and has for an object to provide an improved seam or jointure between the ends of a length of wire mesh, whereby an effective endless belt is produced. It is particularly proposed to secure the ends, by welding, brazing or soldering, in such manner that the joint will have substantially the same characteristics of flexibility and strength as the body of the wire mesh, shall properly support and drain the paper being formed, and shall not cause undue wear to the suction boxes.

A further object is to provide a seam structure which permits the belt to be run in either direction with satisfactory results. This simplifies the installation of the belt in the Fourdrinier machine over those belts which can be run satisfactorily only in one direction.

20 A further object of the invention is to provide a seam which will very effectively hold the adjoining ends of a belt of twill weave, wherein the warp wires pass over one weft wire and thence over two adjacent weft wires, or vice versa, such weave producing less wear on the suction boxes, but by reason of long pickets at the end of the web giving trouble in forming a proper seam.

25 A further object is to provide such a seam structure that the operation of joining the ends of the web may be carried out in a convenient, uniform and economical manner.

30 In forming the seam, we have introduced the novel feature of removing a portion of the final weft wire, which is soldered in place at one end 35 of the web, to produce a flat surface which aligns with the flattened ends of the embracing warp wires, and then abutting the ends of the picket at the other end of the web partly against such final weft wire and partly against its embracing 40 warp wires, and securing such abutting surfaces together. In this manner we obtain a very effective junction of the two ends of the web, without interfering with the flexibility and while maintaining the necessary drainage spaces in the belt. The abutting ends of the pickets may be 45 secured to the weft wire and warp wires by welding, brazing or soldering, as desired, though we prefer to use powdered solder fused by a torch.

50 Suitable applied material, which may be solder, is placed above and below each picket which abuts the flattened final weft wire adjacent the junction to make a gradual surface from the warp wires at one side of the junction to the warp wires on the other side. In this manner, the 55 joint presents rounded knuckles to the junction

boxes below them and to the paper above them in a manner quite similar to the knuckles throughout the body of the web. I also continue such solder or other added material against the flattened final weft wire between the warp 5 pickets of the other end of the web to control the drainage space in such regions.

Our invention comprises the means by which we accomplish the above objects, as well as the method of carrying out the operation, as illustrated in the accompanying drawing and hereinafter more fully described.

In the drawing, which is on a greatly enlarged scale, Fig. 1 is a plan of a portion of a woven wire belt joined by our improved seam; 15 Fig. 2 is a longitudinal section of a joined belt; Figs. 3 and 4 are sectional elevations of end portions of the web before joining, the broken lines indicating the portion which is cut off at the right hand of Fig. 3 and the left hand of Fig. 4 20 before the junction is effected.

Referring particularly to Figs. 1 and 2, the reference numerals 10, 11 and 12 indicate warp wires at one end of the web, and 10a, 11a, and 12a the same warp wires at the other end of the web. 20 indicates any of the weft wires except the final weft wire at the seam, designated 21. The weft wires 20 are round, while the wire 21 is flattened by removing a portion thereof at the end of the web, as shown in Fig. 2. This weft 25 wire 21 is firmly secured to the warp wires above and below it, by solder indicated at 30 in Fig. 2.

The outer face of the final weft wire 21 and the ends of the warp wires which engage it all terminate in the same vertical plane indicated at 35 X—X. The pickets formed by the warp wires at the opposite end of the web also terminate in the same plane but spread vertically a less distance at their ends than the warp ends embracing the final warp wire 21, so that they abut both the 40 flattened final weft wire and an adjacent warp wire. As appears in Fig. 2, some of the warp wires, as 10a, abut the final weft wire 21 and the warp wire 10 above it, while another warp wire, 45 as 12a abuts the final weft wire 21 and the warp wire 12 below it. These members are secured together preferably by soldering.

Where solder is used to joint the ends of fabric, it accumulates as at 31, above the end of the 50 wire 10a and at the end of the wire 10, and also at 32 beneath the wire 10a and adjacent the weft 21. The solder as shown in Fig. 1 adheres closely to the weft 21 and to the ends of the warp 55 pickets so as to make an effective joint there-

between without clogging the openings adjacent the belt.

It results from the above described construction that the two ends of the warp wires are secured together and are also secured to a weft wire to make a very effective seam.

The projection of the warp wires beyond the last retained weft wire at the picketed end of the web is greater than the distance between 10 weft wires throughout the web, so that when such pickets abut the other end of the web the space between the adjacent weft wires at the seam on this side would be greater than the normal spacing. This allows the application of 15 solder along the flattened final weft wire between the pickets as indicated at 34 in Fig. 1, without reducing the drainage space beyond the normal; in fact, such solder furnishes means for controlling the drainage areas in this region as 20 desired.

Due to the above described characteristics of our seam, it is very strong, does not interfere with the flexibility or the drainage of the belt or cause troublesome wear on the suction boxes. 25 It also enables the belt to be run satisfactorily in either direction.

In carrying out our invention, we form a web in the usual manner, then at one end we solder the final weft wire effectively within the warp 30 wires. We then cut away the ends of the warp wires and a portion of the final weft wire back to a vertical plane which leaves about two-thirds in horizontal diameter of the original final weft 35 wire. Such cut-away portions are indicated at Y, in Fig. 3, between the original ends of the web and the final plane X-X. We prefer to bring all of these wires to this plane by a grinding operation.

At the other end of the web, we remove the 40 endmost weft wire, press the end portion of the web together somewhat, and cut away the ends of the pickets back to the center of the region which was occupied by the endmost weft wire, as indicated at Z in Fig. 4, cutting these ends 45 to cause them to terminate in the same vertical plane indicated by the line X-X.

After the formation of the two ends of the web, we abut these ends together, each picket coming 50 against a portion of the flat face of the final weft wire 21 at the other end of the web, and against a portion of the warp wire above or below such weft wire, as the case may be, and we then secure these abutting faces to each other, preferably by powdered solder fused by a torch.

55 Either at the same time, or as a subsequent step, we apply material, preferably solder, around the pickets at the seams and between them against the flattened weft wire and above and below them against the opposite ends of the warp wires, thus 60 making a rounded gradual surface approximately corresponding to the knuckles throughout the web.

Our seam and the method of making it is applicable to various forms of weave effectively joining the warp wires thereof. We have found it especially valuable with a twill weave, in which some warp wires, by passing over or under two adjacent weft wires, leave comparatively long 65 picket portions which have heretofore presented 70 a troublesome factor in the formation of the seam. By our method of joining the ends of the web, by retaining a final weft wire attached to all of the embracing warp wires on one side of the seam, and abutting the warp wires at the other side 75 against such final weft wire, as well as against

the ends of the warp wires, we have overcome this difficulty.

We claim:

1. In a wire cloth belt, a length of woven wire cloth comprising warp and weft wires, the final weft wire at one end having a portion thereof removed to a substantially vertical plane and being secured to the warp wires above and below it, and the warp wires at the other end terminating in a substantially vertical plane and each abutting both part of the final weft wire and part of the warp wires adjacent thereto, such abutting members being secured together.

2. In a wire cloth belt, a length of woven wire cloth comprising warp and weft wires, the final weft wire at one end having a portion thereof removed to a substantially vertical plane and the ends of the warp wires above and below it being all secured together, the warp wires at the other end terminating in a substantially vertical plane and abutting and attached to part of said final weft wire and part of the adjacent warp wire, and material to form a rounded knuckle adjacent the seam at the projecting portions of the ends of the warp wires where they embrace the final weft 2 wires.

3. In a wire cloth belt, a length of woven wire cloth comprising warp and weft wires, the final weft wire at one end having a portion thereof removed to a substantially vertical plane and the 3 ends of the warp wires above and below it all terminating in one plane, the warp wires at the other end terminating in a substantially vertical plane and abutting and attached to part of said final weft wire and part of the adjacent warp 3 wire, and added material adjacent the seam engaging the end surfaces of the warp wires where they embrace the final weft wire and the side surfaces of the warp wires where they abut the final weft wire.

4. In a wire cloth belt, a length of woven wire cloth, comprising warp and weft wires, one end of the length terminating in a plane which passes through the warp wires and through the normal circular boundary of the final weft wire, the other 41 end of the web terminating at a plane passing through warp wires beyond the last retained weft wire, the pickets at the latter end abutting the flattened face of the final weft wire at the first mentioned end, and abutting also the end warp 50 wires, and being secured both to the final weft wire and the warp wires at the first mentioned end, and the applied material surrounding the warp wires at said second end, and abutting the ends of the warp wires and the flattened side of 55 the final weft wire at the first mentioned end.

5. A wire cloth belt comprising a length of woven wire cloth having warp and weft wires, the final weft wire at one end secured to the warp wires above and below it by applied material 60 engaging the weft wire and such warp wires, and the ends of these warp wires and a portion of the final weft wire being removed to a substantially vertical plane when the web is horizontal, the final weft wire at the other end being entirely removed, and the warp pickets beyond it being of reduced spread and cut off to a vertical plane which passes substantially through the center of the space normally occupied by such removed weft wire, the two ends of the web abutting at 70 such severing plane with the ends of said warp pickets abutting part of the final weft wire of the other end and part of the warp wires at such other end, and applied material around the warp pickets which abut the final weft wire, said ma- 75

terial engaging the projecting end surfaces and the other ends of such warp wires and also engaging the flattened face of said final weft wire between the warp pickets.

6. In a wire cloth belt, a length of wire cloth comprising warp and weft wires woven in a twill weave and having a final weft wire at one end, said weft wire having a portion thereof removed to a substantially vertical plane and the warp wires at the other end terminating in a substantially vertical plane and each abutting both part of said final weft wire and part of the warp wire adjacent thereto, and added material securing said final weft wire to warp wires both in the regions where they embrace it and in the regions where they abut it.

7. The method of joining the ends of woven wire web to form a belt, comprising terminating one end of the web in a substantially vertical plane which passes through a portion of a final weft wire, and terminating the other end in a substantially vertical plane passing through the warp wires beyond the last retained weft wire, and then abutting the warp picket of the latter end against a portion of the final weft wire, and against portions of the warp wire ends at the first mentioned end of the web, and securing such abutting faces together.

8. The method of joining the ends of woven wire web to form a belt, comprising cutting off one end of the web back to a plane which passes through warp wires and through a portion of the final weft wire, and at the other end cutting off the warp wires and removing the final weft wire, abutting the warp wires of the latter end against

a portion of the cut off final weft wire and against the cut off warp wires at the first mentioned end, and applying material above and below the warp wires which abuts said cut off final weft wire, such material engaging the ends of the warp wires embracing the final weft wire in a manner to leave rounded knuckles at the top and bottom of the seam.

9. The method of making a woven wire belt, comprising forming a woven wire web, soldering or otherwise effectively joining the final weft wire at one end of the web to the warp wires above and below it, removing the end of the web back to a plane which cuts away approximately one-third of the horizontal diameter of the final weft wire, removing altogether the final weft wire at the other end, reducing the spread of the pickets at such end and cutting them off back to a plane which passes substantially through the center of the region originally occupied by the removed warp wire, then abutting the ends of the warp picket at the last mentioned end of the web as against a portion of the flattened face of the final weft wire and a portion of the ends of the adjacent warp wires at the other end of the web, securing such abutting faces together, and, either at the same time or as a subsequent operation, adding material around the warp wires where they abut the flattened final weft wire, such added material engaging also the final weft wire and the ends of the warp wires above and below such final weft wire.
